UNITED STATES PATENT OFFICE.

JOSEPH JULES PÉRISSÉ, OF ASNIÈRES, FRANCE.

HIGH-EXPLOSIVE SHELL.

SPECIFICATION forming part of Letters Patent No. 595,406, dated December 14, 1897:

Application filed August 2, 1897. Serial No. 646,833. (No model.) Patented in France December 8, 1896, No. 261,999.

To all whom it may concern:

Be it known that I, JOSEPH JULES PÉRISSÉ, of Asnières, (Seine,) in the Republic of France, have invented new and useful Improvements 5 in Shells or Explosive Projectiles, (for which I have obtained Letters Patent in France, No. 261,999, dated December 8, 1996,) which are fully set forth in the following specification.

This invention relates to improvements in 10 shells or explosive projectiles.

When firing projectiles charged with powerful explosives against armor-plates, the explosion of the charge ordinarily takes place immediately after the concussion and before 15 the projectile has passed through or pierced the armor-plate, so that the power of the charge is not utilized except to a slight degree in enlarging the hole produced in the armor-plate. On the other hand, the explosion of the charge sometimes takes place within the gun from the concussion of the gases and causes the bursting of the said gun, the death of the attendants, and sometimes other considerable damage.

Now the object of this invention is to protect the charge and the detonator from the direct action of external shocks, to prevent explosion taking place on firing, and to retard the said explosion to such an extent that 25 it does not take place until after the projectile has passed through or penetrated the armor-plate.

According to my invention I inclose the charge in a jacket or envelop, hereinafter referred to as the "cartridge," which is thin 35 and rigid, but independent of the shell, the form and dimensions of the said envelop being very similar to those of the shell-chamber. The length of the cartridge is slightly 40 less than that of the shell-chamber, so that it can move longitudinally in the shell. At the moment of firing the said cartridge presses with considerable force against the base-plug of the shell on account of its inertia. There 45 is therefore at the moment when the shell strikes an obstacle a small space in front of the cartridge which has to be traversed before the cartridge experiences any effect from the shock, so that a first retardation of the 50 explosive is thereby effected. This retarda-

tion is increased by subjecting the cartridge during its short movement to a powerful retarding but continuously-acting force.

In order that regular results be obtained, it is necessary that the cartridge be made 55 quite rigid. On the other hand, in order that the explosive charge may be as large as possible it is advisable to make the walls of the cartridge as thin as possible.

The cartridge is made rigid and yet of slight 60 thickness by forming the base of the cartridge of a rigid plate or disk, to the circumference of which the edges of the cap forming the rest of the envelop or jacket are secured by any suitable means. This plate or disk is pro- 65 vided with an axial solid rod, which is formed in one with or rigidly connected to it and ex- tends to the other end of the cap. When a detonator is employed, the said detonator is screwed into the cap of the cartridge and into 70 the central rod of the plate or disk. By this means the length of the cartridge and its di- ameter are maintained permanent.

As before stated, it is preferred to increase the retardation of the cartridge produced by 75 the space which it must traverse after impact by placing in said space a retarding substance or cushion, which subjects the cartridge to a continuously-acting resistance. The most effective means I have found for this purpose 80 is what I designate a "hydraulic brake," using liquid friction and resistance.

In the case of liquid friction the space in the interior of the shell is completely filled with a liquid which can flow from the front 85 toward the back of the cartridge, or vice versa. If the diameter of the cartridge be made slightly less than that of the interior of the shell, the flow will take place through the an- 90 nular space thus left, or grooves or passages of sufficient area can be provided in the metal 95 wall of the shell. The diameter measured upon the walls or partitions separating these passages or grooves is then made equal to that of the cartridge at a corresponding point, and the latter is therefore guided in its move- 100 ment. Furthermore, in some cases I may employ a combination arrangement—that is to say, I may provide a cartridge of a diam- eter slightly less than that of the interior of

the shell and add to the annular space thus formed the spaces obtained by the passages or grooves in the metal wall of the shell.

In many cases all obstacles to the forward movement of the cartridge can be dispensed with, the air or other suitable gas being sufficient to act as a retarding-cushion to prevent premature explosion.

The liquid-friction and gaseous-cushion devices have the advantage of producing an equal pressure upon every part of the surface of the cartridge, which is very favorable to the maintenance of the shape of the latter. Furthermore, with the liquid it is possible, without sacrificing anything as regards its good preservation, to choose a liquid which is ignited by the explosion of the charge in such a manner as to give to the shell a certain value as an incendiary projectile.

20 The preceding description has only referred to the retardation of the shock when the projectile strikes an obstacle. It will be obvious that the same means can be employed to obviate the effect of the initial concussion on firing. I, however, advantageously employ the combined arrangements illustrated in the accompanying drawings, wherein—

Figure 1 is a longitudinal section of the cartridge; Fig. 2, a partial section of an apparatus in which is employed the hydraulic retarding device. Fig. 3 is a cross-section of the shell, and Fig. 4 is a detail view of the base of the cartridge.

As shown in Fig. 1, the cartridge is composed of the rigid disk A, forming the base, and the thin jacket A', the cartridge being stiffened by a central rod B, and is provided with a detonator C, which is screwed into the rod B and the cap of the cartridge.

40 The cartridge is of the same general shape as the shell S, but of less length, so that there is space within the latter for the longitudinal movement of the cartridge. In this space is placed the fluid, solid, or plastic retarding-cushion.

As shown in Figs. 2 and 3, the projectile is constructed for a fluid retarding-cushion. To this end the chamber of the shell is provided with a series of longitudinal channels 50 s and is filled with a liquid surrounding the cartridge and producing uniform pressure on its entire surface. This is preferable to other means, such as springs, which might disfigure or break the cartridge upon impact and interfere with its proper action. I have used for this purpose liquids having a neutral fatty base holding in solution salts of feeble stability, rich in oxygen, such as a nitrate or chloride dissolved in glycerin. When the projectile strikes an obstacle, the forward movement of the cartridge is opposed and retarded by the resistance of the fluid, which requires an appreciable time to pass through contracted channels from the front to the rear of the 65 chamber.

The cartridge plate or disk A is provided

on its under side with a number of radiating ribs b, which before firing are in contact with a lead plate D, fixed to the base-plug P of the shell. A small rod D', of malleable metal, (copper or brass,) is fixed to the center of the plate or disk, passes through the plug in a direction axial to the shell, and is formed with a screw-thread on the end which projects from the plug and is screwed into the base A of the cartridge. A nut F is screwed upon the threaded end of the rod and bears against the plug. By this means the three parts—namely, the cartridge, leaden plate, and shell-plug—are secured together. On firing, the small rod is slightly flattened or compressed and the ribs press into the lead, thereby anchoring the cartridge, insuring the rotation thereof with the shell, and all the liquid or the gas is forced toward the front of the cartridge. In order to allow for compression of the rod D', I provide in the base of the shell a space or pocket p. At the shock of the impact with an obstacle the small rod breaks, and the cartridge is thereby free to continue its movement forward, except in so far as it is exposed to the resistance of the retarding liquid or gas.

Having thus described my invention, what I claim as new, and desire to secure by Letters Patent, is—

1. An explosive projectile comprising in combination a shell, an inclosed cartridge independent of the shell and of similar shape but shorter than the chamber of the shell so as to leave a free space between the forward end of the cartridge and the shell, and a cushion in said space for retarding the forward motion of said cartridge the latter being initially held at the rear or base of the shell, substantially as described.

2. An explosive projectile comprising in combination a shell, an inclosed cartridge of less length than the shell, and composed of a relatively thick rigid disk composing the bottom, thin side walls and a central stiffening-rod, and means for retarding the movement of the cartridge from the rear to the front of the shell, the cartridge being held initially at the rear or base of the shell, substantially as described.

3. The combination of the inclosing shell, the cartridge of less length than the shell, so as to leave a space through which it moves relatively to the shell after impact, a retarding-cushion occupying said space, and a soft-metal plate or disk against which the base of the cartridge bears, substantially as described.

4. The combination of the shell, the inclosed cartridge shorter than the chamber of the shell so as to leave a space between the forward end of the cartridge and shell, and a fluid retarding-cushion filling said space, the cartridge being initially held at the base or rear of the shell, substantially as described.

5. The combination of the shell, the in-

closed cartridge shorter than the chamber of the shell, the cartridge being initially held at the base of the shell, and a liquid retarding-cushion in the space between the shell and cartridge, substantially as described.

6. The combination of the shell, the inclosed cartridge of less length than the chamber containing it, said cartridge being initially held at the base of the shell, the latter being provided with longitudinal contracted channels, and the liquid retarding-cushion occupying the space between the shell and cartridge, the construction constituting a hydraulic brake retarding the forward movement of the cartridge after impact, substantially as described.

7. In an explosive projectile the combination of the shell, the rigid inclosed cartridge of less length than the shell, the base of the cartridge having radial ribs, a disk of soft metal between the cartridge and base of the shell, and a fragile connection between the shell and cartridge adapted to be ruptured upon impact of the projectile, substantially as described.

In testimony whereof I have signed this specification in the presence of two subscribing witnesses.
